W. O. LAWRENCE

COMBINED LOCK AND LATCH

Filed March 22, 1924

Juvenile

William O. Lawrence

By *Herbert E. Smith*

Attorney

UNITED STATES PATENT OFFICE.

WILLIAM O. LAWRENCE, OF SPOKANE, WASHINGTON.

COMBINED LOCK AND LATCH.

Application filed March 22, 1924. Serial No. 700,989.

To all whom it may concern:

Be it known that I, WILLIAM O. LAWRENCE, a citizen of the United States, residing at Spokane, in Spokane County, and 5 State of Washington, have invented certain new and useful Improvements in Combined Locks and Latches, of which the following is a specification.

My present invention relates to an improved combined lock and latch especially applicable for use in connection with doors for garages and other buildings, and while the invention is hereinafter referred to as applied to a hinged door, it will be understood that with slight alterations the device 10 of my invention may be utilized in connection with sliding doors or other similar objects.

The primary object of the invention is the provision of a simple and compact arrangement of a locking device at the exterior side of the door in combination with a normally closed latch device at the interior side of the door, and means whereby the locked 15 door may be unlatched from the interior, but can only be unlatched from the exterior after the exterior lock device has been released.

The invention consists in certain novel 20 combinations and arrangements of parts as will hereinafter be more fully set forth and claimed.

In the accompanying drawings I have 25 illustrated one complete example of the physical embodiment of my invention in connection with a hinged door, wherein the parts are combined and arranged in accordance with the best mode I have thus far devised for the practical application of the 30 principles of my invention.

Figure 1 is a vertical sectional view of a portion of a locked door and its upper frame bar or transverse casing, showing also the relation thereto of the combined lock 35 and latch of my invention.

Figure 2 is a perspective view of the combined lock and latch, detached.

Figure 3 is a horizontal sectional view 40 through a portion of the door and adjacent wall, showing the combined lock and latch in top plan.

In order that the general assembly and relation of parts may readily be understood I have designated part of a hinged door as 45 D, and the door casing or adjacent wall as C and the top, transverse bar of the door cas-

ing as T. At the interior side of the door is located a latch 1 disposed in approximately horizontal position and provided with a head 2. The latch is pivoted at 3 in 60 the casing 4 which is secured near the top of the door and is carried thereby. The hook of the latch is designed to co-act with a keeper slot 5 in the under face of the transverse bar T of the door frame, and normally 65 the hook is in engagement with the keeper to hold the door against opening movement. The latch is retained in closed position by means of a flat spring 6 located in the casing and having its upper end in engagement 70 with a notch or shouldered end 7 of the latch. The tension of the spring may be adjusted by means of the adjusting bolt 8 threaded in the nut 9 affixed to the casing, and a pin 10 extending transversely through 75 the casing performs the function of a fulcrum for the spring when pressure is applied at its end below the fulcrum for adjusting the tension of the spring with relation to the latch. By pressing in on the 80 lower end of the spring the upper end will be caused to bear with greater force on the pivoted latch to cause its engagement with the keeper therefor. The pivoted movement of the latch is limited by its engagement with the top wall of the casing and 85 also by the spring.

At the interior side of the door the latch may be released from its keeper by a pull on the flexibly connected bars 11 and 12, 90 the former being connected to the latch by pivot in one of the selected holes 13 of the latch, and the bars are pivoted together at 14 in order that they may swing toward the right in Figure 1 to angular position 95 for releasing the latch. This swinging movement pulls the latch down to its dotted position in Figure 1 for releasing the hook from its keeper. When the pull on the bars is released, the spring 6 returns the latch and 100 these bars to normal position.

The latch may also be released from the exterior of the building or from the outer side of the door D, and for this purpose I use a bell crank lever 15 pivoted to the 105 bracket 16 which is secured at the inner side of the door D and is movable in a vertical plane. The lower bar 12 is pivoted to the bell crank lever as shown, and a link 17 is also pivoted to this lever. The link is 110 disposed in an approximately horizontal position and at an angle to the pull bar 12, and

is pivotally suspended between the bell crank lever and a shank 18 provided with an end knob 19 and passed transversely through the door which is slotted at 20 for this purpose. The shank and knob are rigid with the hasp 21, a joint 22 being indicated in Figure 2 between the hasp and shank, and the hasp is pivoted at 23 to the exterior of the door below the slot.

10 It will thus be seen that by grasping the knob and pulling thereon the hasp is swung on its pivot or hinge 23 and the pivotally suspended link 17 between the shank and bell crank lever draws on the latter to swing it on its pivot 16'. This movement of the bell crank lever is transmitted to the flexible pull bar comprising members 11 and 12 of the latch, and the latch is thereby released from the exterior to permit opening of the 20 door in usual manner.

The hasp is normally locked against this opening movement by the utilization of a padlock 24 or other locking device in connection with a staple 25 which has an attaching plate 26 secured at the outer side of the door and which projects through a suitable opening in the hasp provided therefor.

Thus when the padlock is locked in the

staple over the hasp the latter cannot be 30 turned on its hinge for releasing the latch 1 until the padlock has been unlocked and withdrawn from the staple 25.

Having thus fully described my invention, what I claim as new and desire to secure by Letters Patent is—

1. The combination of a casing, a normally closed spring pressed latch pivoted in the casing and operating mechanism at the inner side of a door comprising a pair of 40 pivoted pull bars pivotally connected to the latch, a bell crank lever pivoted at one end of one of said bars, a link pivoted to said lever, an exterior pivoted hasp having a knob thereon and a shank on said hasp 45 pivoted to said link, and means for locking said hasp.

2. The combination with a normally closed latch and its flexible operating mechanism at one side of a door, of a bell crank 50 lever connected with said mechanism, a link connected to one arm of said lever, a hasp pivoted at the outer side of the door, an angularly disposed shank on the hasp pivoted to said link, and means for locking the 55 hasp.

In testimony whereof I affix my signature.

WM. O. LAWRENCE.
